GAME

Park W. T. Loy, Hagerstown, Md.

Application June 10, 1932, Serial No. 616,530

6 Claims. (Cl. 273—131)

In the present invention I provide a game including a game board and movable game pieces and it is an object of the invention to play the game after the fashion of a national election campaign in order that by skillful maneuvering a player may capture a majority of electoral votes to win the game.

A further object of the invention is to provide a game simulating a national election campaign in which a playing territory or public domain is provided over which the States are movable for preferential positioning, optional with the player, but governed by certain rules, with the hazard of capture by the opposing player or candidate, should the State pass into territory over which the opposing player or candidate has domain.

A further object of the invention is to provide a game including a playing surface over which game pieces are movable according to certain rules, the surface being zoned in order that by skillful maneuvering a player can advance his player pieces over a predetermined area into the zones.

25 Other objects of the invention will be apparent from the following description of the present preferred form thereof, taken in connection with the accompanying drawing, wherein—

The figure is a top plan view of a game board 1 constructed in accordance with the present invention, showing some of the game pieces mounted thereon, the latter being also shown in plan.

The device of the present invention consists of a game board 1, which may be made of wood, metal, cardboard, or other suitable material and if desired, may be hinged at 2 in order to permit folding of the board in a manner well known in the art. The board is divided into two fields, generally designated 3 and 4, along the line of the hinge 2. Preferably the playing surface of the board is divided into a predetermined number of uniform squares, in the present instance three hundred and seventy-four being shown, seventeen squares constituting the playing width of the present board and twenty-two squares the playing length thereof. Each of the fields 3 and 4 is divided into seventeen squares in width and eleven squares from the starting or base line 5, to the central or dividing lines of the fields, 6. Consequently, one hundred and eighty-seven squares comprise each field. One hundred and eleven of the squares of each field, designated 7, are open, through which game pieces, hereinafter described, are movable. The remaining seventy-six squares of each field, designated 8, are closed

or solid squares and constitute forbidden areas into which, or over which the player pieces may not be moved. Certain of the open squares in each field are provided with circles or dots 9, the circles or dots of one field being of a color 5 different from the circles or dots of the other field. The squares which contain the circles or dots are the starting positions for the player pieces hereinafter described.

Each of the playing fields 3 and 4 is also provided with an isolated territory which runs parallel to the line of play of the game pieces on the board, these territories being strategic positions and consisting of specially designated blocks or squares 10. In the present instance, I prefer 10 to employ four such squares in each playing field, each of said squares being designated by a cross mark (X) mounted in a heavy border. The squares 10 of one field correspond in color to the dots 9 of the opposite field. 20

On the opposite sides of the territory constituting the strategic position of each field, I provide, at the base line 5 of each field, a series of blocks 11, constituting conceded States' zones. Each of these zones, in the present instance, I 25 show to consist of five aligned squares to which access may be gained through three open squares.

The player pieces may be of any desired shape and size, but I have found discs, designated in the drawing at 12, to be adapted for use in this connection. Each disc is provided with indicia representative of a State and the number of electoral votes of the particular State designated. Two discs are provided for each State, in order that each player at the beginning of the game 35 will have a player or game piece representative of each State in the Union, with the number of electoral votes of each particular State.

The game may be played by two persons, each of whom may be regarded as a candidate for 40 office. The forty-eight player pieces of each candidate are mounted in the squares containing the circles or dots. Of course, the particular manner of positioning the player pieces according to their values is optional with the player, but it is manifestly advantageous to protect the States having the larger values as much as possible and hence, these are usually retained as far away as possible from what may be called the territorial dividing line 6 between the two fields of the contestants. 45 The purpose of the game is for one candidate to obtain a majority of the electoral votes and with this end in view, the player pieces are manipulated on the board at the option of the player, but within the bounds of certain rules. To have 50 55

votes counted, it is necessary that the player pieces move from one field across the dividing line 6 into the opposite field and traverse the opposite field completely until the advancing pieces are finally lodged in the conceded States' zones at the playing extremity of the field. The player pieces are movable along the board similar to the game of checkers, except that the player pieces may be initially moved laterally in the open spaces 1 as well as forwardly. Since the player pieces of each contestant are of a different color, it is easy to segregate the States of the two contestants. In beginning the game, each player may move any player piece desired forwardly or from side to side in any open space. As soon, however, as the State or player piece of one player comes adjacent the State of the opponent, the latter, in advancing, may leap or jump said adjacent State and multiple leaps or jumps are permitted, as in the game of checkers. The States captured in this way of course, go to the credit of the capturing contestant. In jumping or leaping an adjacent State or States, it is to be understood that this movement is not to be confined in one direction only, but may be forward or to the right or left, or any combination of forward, right and/or left. Additionally, it is the desideratum of the game to provide forced leaps or jumps, when profert is made of such a leap by an opposing candidate to the exclusion of another jump or leap available to said opposing contestant. Each player or contestant has the four strategic positions designated 10, which are located in close proximity to the conceded States' zones in the opponent's territory. The strategic positions may be occupied by the player pieces or States of either player or candidate when found vacant, but where a player's own State occupies a strategic position in his own field, he is not immune from attack or capture. On the other hand, where these strategic positions are occupied by a candidate in the opponent's field in his forward advance, such State is immune from attack and capture, but may attack the States of the opponent coming in the squares adjacent thereto. Preferably, although a State may occupy a strategic position in the opponent's field with immunity from attack, nevertheless this State can be leaped or jumped without capture to effect the capture of one or more States found in eligible position beyond the strategic zones. After an opponent has successfully maneuvered his player pieces or States through his own field and the field of his opponent to the conceded States' zones of said opponent, such States' votes are immediately credited to the capturing contestant and in addition, said State is returned to play with increased value in that it may move backward in addition to forward and right and left, similar to a king in checkers. To designate the increased value of the particular State, an additional disc of similar coloring is superimposed thereon. The conceded State, in continuing to play, has all the previous rights which it enjoyed, in addition to being permitted to move backward as well as forward, but it has no scoring value if captured. When a State of either candidate is captured by being jumped or leaped and is removed from the board, the corresponding State of the opponent remains in full play, but the indicia bearing side of the disc is turned downwardly and of course, has no scoring value, if later captured.

75 In scoring the game, the player first obtaining

a majority, namely, two hundred and sixty-six votes, wins the game.

It is to be understood that in the drawing I have shown a board and game pieces which I have found to be especially adapted for use in playing the game after the teaching of the present invention. I am aware however, that the game may be played by a rearrangement of the squares and game pieces and that changes may be made in the game board and game pieces, without departing from the spirit and scope of the invention as covered in the claims appended hereto.

What is claimed is:

1. A game simulating a national presidential election campaign including a game board divided into a plurality of squares separated by a central dividing line to provide two fields, player pieces mounted on the board with indicia thereon representative of the States and their electoral votes, said pieces being movable in a limited number of the squares of each field, certain of the squares of each field being designated as privileged zones for the player pieces and other of said squares at opposite extremities of the board being the objectives of the player pieces. 15
2. A game simulating a national presidential election campaign including a playing surface divided into two fields, each of which consists of an equal number of squares, player pieces movable over certain squares of the playing surface, a plurality of squares in each field running parallel to the line of play, being specially marked to provide designated zones endowed with special privileges, and a further group of squares at the opposite extremities of the playing surface being designated to form the objective of the player pieces. 20
3. A game simulating a national presidential election campaign including a player board divided into a plurality of squares separated by a central dividing line to provide two fields, duplicate sets of player pieces with indicia representative of the States and their electoral votes, each set consisting of forty-eight pieces mounted in certain squares in each field and adapted for movement across the dividing line into the other field through certain unoccupied squares of the latter, certain of the squares in each field bearing a characteristic declaration indicative of certain privileges, additional squares in each field being designated to constitute the objective points of the States. 25
4. A game simulating a national presidential election campaign including a playing board divided into a plurality of open and closed squares separated by a central dividing line to provide two fields, certain of said open squares having indicia therein to designate starting points, other of said open squares being demarcated to indicate privileged zones, player pieces of different values mounted in the open squares of each field adapted for movement across the dividing line from one field to another only in the open squares, certain of the open squares at the outer extremity of each field being unmarked to provide conceded States' zones forming the objective of the player pieces. 30
5. A game including a playing board with a plurality of open and closed squares thereon, the board being centrally divided to provide two playing fields, alternate rows of the open squares having indicia therein indicative of starting positions, certain of the open squares of each field being specially demarcated to indicate privileged 35

zones, certain of the open squares at opposite terminals of the board being grouped to provide conceded States' zones, and game pieces for movement over the board in open squares of the latter.

5. 6. A game including a playing board composed of open and closed squares, the board being centrally divided to provide two playing fields, a majority of the squares of each field being open, certain of which are centrally marked, a further

predetermined number of said open squares being peculiarly demarcated to constitute strategic positions of one field corresponding to the centrally marked open squares of the opposite field, and game pieces movable on the board in all said open spaces including the said centrally marked squares and strategic zone. 5
